MIXING-VALVE.

1,269,482.

Specification of Letters Patent. Patented June 11, 1918.

Application filed November 17, 1916. Serial No. 131,865.

To all whom it may concern:

Be it known that we, JOSEPH B. MERIAM and HOWARD W. PRICE, citizens of the United States, residing at Cleveland, in the 5 county of Cuyahoga and State of Ohio, have invented a certain new and useful Improvement in Mixing-Valves, of which the following is a full, clear, and exact description, reference being had to the accompanying drawings.

The object of this invention is to provide a very simple and effective controlling valve for causing a proper mixture of gaseous hydro-carbon and air, and for feeding 15 the same in regulated quantities. Our valve acts as a mixing valve or gas carburetor, and is designed to receive a gaseous hydro-carbon under pressure, which, with the proper admixture of air, may be fed to an 20 internal combustion engine.

One of the uses of our gas carburetor or mixing valve is in the testing of automobile engines by the use of natural or artificial gas. Our valve is arranged so that it may 25 be given the desired opening easily and quickly. It is provided with a very simple and effective damper in the air passageway, which may be shifted to different positions, thus enabling the engine to run normally or to race, as desired in testing. Another feature of our valve is that it may 30 furnish a small quantity of gas (with or without air admixture) for starting the engine.

The mechanism accomplishing the above 35 results, and constituting the subject matter of this invention, is hereinafter more fully explained and the essential characteristics are set out in the claims.

In the drawings, Figure 1 is an elevation 40 of our gas carburetor, looking at the intake side; Fig. 2 is a plan of our carburetor; Fig. 3 is a sectional elevation approximately on the line 3—3 of Fig. 2, the plug being 45 shown in full side elevation; Fig. 4 is a horizontal cross section through the carburetor at the exit passageway; Fig. 5 is a side elevation, partly broken away, of the valve plug; Fig. 6 is a detail, in sectional 50 elevation, showing the gas bypass, for starting, the plane of the section being the same as that of the corresponding parts in Fig. 3, but the valve plug being in a different position; Fig. 7 is a fragmentary view

illustrating different positions of the air 55 damper and the action of the spring in holding the damper in either extreme position.

Our carburetor consists primarily of a casing having intake passageways for gas and 60 air and an exit passageway for the mixture, and a plug within the casing rotatable and longitudinally shiftable therein, for coupling the passages as desired. The longitudinal shifting is effected by a stationary 65 cam on the casing, which causes the shifting when the plug turns, and a spring is provided to oppose the cam and hold the plug in position. Other features are a controlled 70 by-pass for the gas for starting purposes, 70 and a shiftable air damper, all of which will be described more in detail.

Referring first to the casing, 10 indicates an outer, approximately cylindrical, wall, and 11, 12 and 13 aligned inner walls having 75 a cylindrical inner surface, or bore, and thus adapted to receive a cylindrical valve plug, hereinafter described. The inner walls mentioned are spaced from the outer wall 10 to leave annular passageways between 80 them. Thus the inner wall 11 is connected with the outer wall by the top portion 15 of the casing; the wall 12 is connected with the outer wall by a horizontal partition member 16, and the wall 13 is connected 85 with the outer wall by a horizontal portion 17. Extending downwardly from the inner wall 13 and the offset portion 17, is a substantially cylindrical extension 18, forming 90 an intake passageway 19 for air.

Between the inner walls 12—13 and the outer wall 10, is an annular passageway 20 communicating with the gas intake 21 formed in a boss 22 on the outer wall 10. An annular passageway 25 between the 95 outer wall and the inner walls 11—12, communicates with an exit passageway 27, occupying a tubular extension 28. This extension is shown as provided near its end with a plate 29, whereby it may be attached 100 to the intake manifold of an engine. This plate may, if desired, be swiveled on the extension 28, and such is the form shown in Figs. 3 and 4. Between the inner walls 12 and 13 is an annular port 30 connecting the 105 annular gas passageway 20 with the interior of the casing. Similarly between the inner walls 11 and 12 is an annular port 31

connecting the interior of the casing with the discharge passageway 27.

To control the admission of gas through the annular port 30 and the discharge of the 5 same, together with air received from the tubular passageway 19, we provide a rotatable shiftable plug 40. This plug has a cylindrical exterior and is substantially hollow, its interior being in open communication 10 with the air passageway 19. The plug is closed at the upper end, as shown in Fig. 2, and is there provided with a handle 43 extending laterally and furnishing means for turning it. Intermediate of its body the 15 plug is encircled by an annular slot 44 which divides its exterior into two separated cylindrical walls 41 and 42. To support the lower wall 42 of the plug and connect it with the upper portion, we provide inner webs 45, 20 which preferably radiate from the axis of the plug and are connected with both of its walls. The drawing shows four of these webs, which may be conveniently cast integrally with the walls and handle of the plug. 25 The lower wall 42 of the plug is adapted to entirely close the annular opening 30 in one position of the plug, as shown in Fig. 3. This wall 42, however, is provided with an opening 47, which may be brought into registration with the port 30, by longitudinal 30 movement of the plug. The same longitudinal movement carries the annular opening 44 into registration with the port 31, so that the gas admitted to the interior of the plug 35 from the port 30, and air coming into the interior from the passage 19, are discharged through the annular opening 44 into the port 31 and thus outwardly through the discharge passageway 27.

40 To readily effect the longitudinal shifting of the plug, to cause the registration described, we provide on the top portion of the casing a stationary cam 35, which is engaged by a suitably formed boss 49, on the 45 under side of the handle 43. Accordingly, the turning of the plug by the handle (toward the right in Fig. 1) causes the plug to rise in the casing, whereby registration is effected between the opening 47 and the port 50 30, and the opening 44 and the port 31. A stationary abutment 36, at the end of the high point of the cam, limits the opening movement of the lever. The closing movement is conveniently regulated by a screw 55 threaded in an ear 37 on the casing and forming an abutment for the side of the lever. This screw is shown as locked by a suitable jam nut 51.

To apply downward force to the plug, 60 keeping the handle-boss 49 always in snug engagement with the cam, we provide a tension spring 60, which is suitably anchored at its lower end and extends upwardly into the interior of the plug and is secured thereto 65 by having a hooked upper end 62 passing

through an opening in one of the webs 45. This spring prevents the valve plug from accidental displacement. At the same time it does not interfere with the ready turning of the plug by the handle. The incline of the cam 35 is gradual enough so that the plug will remain wherever placed.

So far as the operation of the valve plug is concerned the lower end of the spring 60 might be anchored to any convenient member, but we avail ourselves of this same spring in holding the air damper in place by anchoring the spring to the air damper, which we will now describe. The air damper consists of a disk 70 having a diameter 80 approximately equal to the internal diameter of the tubular extension 18. This disk is provided with trunnions 71 and 72, which are journaled in the casing, which is preferably provided with diametrically opposite 85 bosses to constitute the bearings. The trunnions may be in the form of pins bifurcated to receive the disk 70, and may be held on the disk by screws 73, or other means. The trunnion 72 extends outside of the casing 90 and there has a handle 75 furnishing means for swinging the disk to vary the effective opening. We form in the disk a radial slot 76, and adjacent to its inner end is a hole 78. The lower portion of the spring 60 extends 95 downwardly through the slot 76 and is provided with a hook 63 which extends upwardly through the hole 78. The tension of this spring pulls the damper trunnions snugly against their bearings. Moreover, 100 the hole 78 is slightly off the center so that the spring tends to hold the damper in either extreme position, and when it is thrown past the center, in changing from one position to the other, may snap it into the extreme position. The radial slot 76 allows the damper to be thus turned. An enlargement 77 of the inner end of that slot provides for the travel of the spring when the plug is turned.

To adjustably limit the positions of the 110 air damper, we form on the body of the casing ears 38 and 39, which are occupied by screws 80 and 81, which form abutments for the lever 75 and thus limit the position of the air damper. These screws are preferably provided with jam nuts 82. The screws are preferably so adjusted that one extreme position of the air damper is suitable for the usual running of the motor, and the other extreme position for racing the motor. This 115 enables tests to be made very rapidly, as the operator shifts the handle 43 to turn on varying amounts of gas, with the air damper in the normal position, and then by simply throwing the air damper he can race the 120 motor and thus make further tests.

To start the motor, it is desirable to provide for the admission of undiluted gas, or gas mixed with an abnormally small amount of air. To accomplish this, we provide a 130

bypass controlled by the plug 40. This bypass consists of openings 90 and 91 through the inner wall 12 from the annular passages 20 and 25 respectively, and a recess 92 formed in the plug wall 42 and adapted to couple the openings 90 and 91. The discharge area of the opening 91 is regulated by the pointed set screw 95, which acts as a needle valve, this screw being clamped by the nut 96. The recess 92 extends for a short distance about the plug 42 and is in inclined position, as shown in Fig. 5, and is thus adapted to effect communication between the ports 90 and 91, notwithstanding the rising of the plug.

In closed position of the valve the openings 44 and 47, and the recess 92 are all out of registration with their coöperating ports. Fig. 3 shows the relation of the bypass ports and the plug after the plug has been moved to the starting position. Fig. 6 shows the parts after the valve plug has been turned and has risen farther, but with the recess 92 still in coöperation with the ports 90 and 91. A little further turning of the plug, then corresponds to the position illustrated in Fig. 6, carries the recess 92 laterally away from the ports and thus closes the bypass.

As it may be desirable to supply a small amount of air with the bypassed gas used in starting or in warming the motor, we provide for this by forming an arcual notch 97 in the lower edge of the plug wall 41, or, in other words, we increase the opening 44 at this point to overlap the port 31. This notch or increased opening, is inclined or gradual, as shown in Fig. 3. The bypassing recess 92 allows the same amount of gas to bypass in any of the positions of the plug where the recess is active at all, but the amount of air admitted when the gas is bypassed may be regulated by the position of the plug, owing to the incline of the notch 97. Shortly after the plug has been raised far enough for the notch 47 to come into registration with the port 30, the recess 92 passes out of action.

Having thus described our invention, what we claim is:

1. The combination of a casing having 50 intake and exit ports, a movable hollow plug within the casing adapted to control communication between said ports and having a port through its wall, an air passageway communicating with the interior of the plug, 55 a damper in said passageway, a tensile spring within the casing anchored at one end to the damper and at the other end to the valve plug, and means for moving the plug longitudinally and rotatively to change its 60 presentation to the ports.

2. The combination of a casing having an internal bore with ports in it, a hollow plug occupying said bore and having openings 65 for establishing communication between the ports through the interior of the plug, means for admitting air into the interior of the plug, and a bypass between said ports in the casing, said bypass including a recess in the plug.

3. The combination of a casing having an internal bore, two passageways within the casing outside of said bore, ports from said passageways into the bore, a plug within said bore controlling communication between said ports, two openings into the bore from the respective passageways independent of the ports, a recess in the plug adapted to establish communication between said openings, and a pointed screw adapted to act as a needle valve with one of said openings.

4. The combination of a casing having an internal cylindrical bore, intake and exit passageways terminating in ports at said bore, a cylindrical valve plug occupying said bore, means for turning the plug, means for causing the plug to move longitudinally when turned, and a bypass between said ports, said bypass including a recess in the exterior of the plug.

In testimony whereof we hereunto affix our signatures.

JOSEPH B. MERIAM.
HOWARD W. PRICE.
